UNITED STATES PATENT OFFICE.

TRACE S. FORD, OF MARSHALLTOWN, IOWA.

COUNTING-BOARD.

No. 888,425.

Specification of Letters Patent.

Patented May 19, 1908.

Application filed October 20, 1906, Serial No. 339,860. Renewed March 7, 1908. Serial No. 419,767.

To all whom it may concern:

Be it known that I, TRACE S. FORD, a citizen of the United States, residing at Marshalltown, in the county of Marshall and 5 State of Iowa, have invented a new and useful Counting-Board, of which the following is a specification.

This invention relates to counting boards which are adapted particularly for use in 10 cribbage and similar card games.

The object of the invention is to improve the construction of counting boards in such manner as to adapt them to be used for holding a plurality of sets or "hands" of cards, 15 whereby, after a number of "hands" have been played by one of the players, they can be played a second time by another of the players, thus reducing to a minimum the element of chance due to the holding by one 20 player of better cards than those held by the other.

With the foregoing and other objects in view, which will appear as the description proceeds, the invention resides in the combination and arrangement of parts and in the 25 details of construction hereinafter described and claimed, it being understood that changes in the precise embodiment of invention herein disclosed can be made within the scope of 30 the following claims without departing from the spirit of the invention or sacrificing any of its advantages.

In the accompanying drawings forming part of this specification:—Figure 1 is a perspective view of a counting board constructed in accordance with the present invention and adapted for use in playing a game such as 35 duplicate cribbage; Fig. 2 is a longitudinal vertical section through one-half of the board illustrated in Fig. 1; Fig. 3 is a plan view of a slightly modified construction in which the board is rigid and is not adapted to fold as is the case in the construction shown in Fig. 1; Fig. 4 is a perspective view of a modified 40 form of folding board; Fig. 5 is a longitudinal vertical section through one side of the board illustrated in Fig. 4; Fig. 6 is a plan view of a modified form of rigid or non-folding counting board; Fig. 7 is a perspective view of an 45 other modified form of folding board; Fig. 8 is a longitudinal vertical section through one-half of the board illustrated in Fig. 7; Fig. 9 is a plan view of another modified 50 form of rigid or non-folding board. Fig. 10 is a perspective view of another modified 55 form of folding board. Fig. 11 is a plan

view of a further modified form of rigid board. Fig. 12 is a longitudinal sectional view taken on the line 12—12 of Fig. 11.

Like reference numerals indicate corresponding parts in the different figures of the drawings.

In carrying out the present invention, it is proposed to provide a counting board with means for holding a plurality of sets or "hands" of cards in inclined position so that their faces cannot be seen, and separated from each other in such manner that they can be readily removed from the board without mixing one "hand" with another. At 70 the end of each deal, after the "hands" have been played in the usual manner, each player places his cards, face downward, in an inclined position, in the counting board. The different trump cards are also placed in an 75 inclined position in one or more compartments which are provided for the purpose. At the end of the first portion of the game, when all the "hands" have been played and placed in the counting board, the players 80 either reverse the counting board or otherwise remove the cards, one set at a time, so that each player will use the "hands" which have been previously played by his opponent.

In the embodiment of invention illustrated 85 in Figs. 1 and 2, the counting board consists of a plurality of sections 1, 1, which are hinged together, as indicated at 2. The sections 1 are formed in their inner faces with recesses such as 3 which are adapted to receive the cards when the board is closed. Each of the sections 1, in the outer face thereof, is formed with a plurality of sockets 4 which are adapted to receive the counting 90 pegs in a well-known manner.

The means for holding a plurality of sets or "hands" of cards in an inclined position and separated from each other preferably consists of a plurality of inclined slots 5 which extend inward from the outer surface of each 95 section 1 and are produced by means of suitable partitions 6.

In playing a game such as cribbage, etc., one of the players uses one section of the board and the other of the players uses the 105 other section of the board. After the "hands" have been played, the players place the cards, face downward, in the inclined slots 5. The trump card, after each play, is placed face downward in the trump slot 7, at 110 the end of the section of the counting board belonging to the dealer. A door 8 for each

trump slot 7 preferably is pivotally mounted, as indicated at 9, so that when the counting board is not in use, the counting pegs can be placed in the trump slot and the door closed.

5 After the desired number of hands have been played, the counting board is turned around and each player then plays the "hands" which were previously played by his opponent, at the same time using the trump cards 10 by removing the bottom card.

The slots 5, by holding the cards on an incline, serve to prevent the faces thereof from being seen, and the partitions 6, by separating the different "hands" from each other, 15 permit the cards to be readily withdrawn without causing them to become mixed.

In the embodiment of the invention illustrated in Fig. 3, the board is rigid or non-folding, and the sets of inclined slots 10 for 20 the different players are separated from each other by a longitudinal partition 11, and furthermore, only a single trump slot 12 is provided for the use of both players, said slot having a door 13. In other respects, the 25 counting board is constructed in the same manner as that illustrated in Fig. 1.

The modified construction illustrated in Figs. 4 and 5 is the same as that illustrated in Fig. 1, except that the partitions 6 are dispensed with and the cards are held in inclined position by means of transversely-extending rods 14 which are fitted at their ends into suitable grooves formed in the counting board and are held in said grooves by means 30 of retaining plates 15. It will be obvious that when a "hand" of cards is fitted down between two of the rods 14, one of said rods will rest against the under surface of the cards and the other of said rods will rest 35 against the upper surface thereof and will thus hold said cards in inclined position with their faces downward so as not to be exposed to view.

The modified construction illustrated in 45 Fig. 6 is practically the same as that illustrated in Fig. 4, except that the counting board is non-folding and a longitudinal partition 16 is employed for bracing the central portions of the rods 14 and for dividing the 50 board into two sets of compartments to receive the cards of the different players.

In the construction illustrated in Figs. 7 and 8, the means for holding the cards in inclined position preferably comprises a plurality of ribs 17 which are provided in each section of the counting board. Each of the ribs 17 is formed with a straight face 18 and an inclined face 19. Secured against the outer surface of each section of the counting 55 board is a plate 20 having slots 21 adapted to receive the different sets of cards so as to press them against the inclined surfaces 19 of the ribs 17 and thus hold them in proper position. The trump slot 22 is undercut, as 60 indicated at 23, in such manner as to hold

the trump-cards in an inclined position and extending in a direction opposite the other cards.

The construction illustrated in Fig. 9 is the same as that illustrated in Figs. 7 and 8, except that the board is non-folding and only one trump slot is employed.

In Fig. 10 of the drawings there is illustrated a modified form of folding board in which the top of the board is formed with a recess covered by a metal plate 25, said plate being formed with spaced slots 26 the walls of which are bent downwardly to produce inclined partitions or slats 27 adapted to support the different sets or hands of cards 80 in inclined position. The plate is also formed with an opening 28 having one wall thereof inclined in the opposite direction or towards the base of the adjacent partition 27 for supporting the trump cards in reverse inclined position.

In Figs. 11 and 12 the board is similar in construction to the board shown in Fig. 10 only the former is rigid or non-folding, both sets of slots 26' and partitions 27' being 90 stamped out of a single plate or strip of metal, as shown.

While the counting board is principally designed for playing cribbage it is obvious that the same with certain minor variations may 95 be used with equally good results when playing other games of cards.

The improved counting board of the present invention is strong, simple, durable and inexpensive in construction as well as thoroughly efficient in use.

Having thus described the invention what is claimed is:

1. A counting board including a receptacle having means for holding a plurality of sets or hands of cards in parallel relation and in inclined position with the sets separated from each other, and means independent of the card holding means and disposed in advance of and arranged in alignment with 105 said card-holding means for supporting a card or cards in synclinal relation to the several sets of cards.

2. A counting board including a substantially rectangular frame having parallel side walls connected by end walls, means interposed between the side walls and forming independent compartments for holding a plurality of sets or hands of cards in the same inclined position, and means spaced 110 inwardly from one end of the frame and independent of the means for holding the several sets or hands of cards and in alignment therewith for supporting a card or cards in synclinal relation to the several sets. 115

3. A counting board comprising a plurality of pivotally united sections each formed of spaced inclined slats defining slots for receiving and holding a plurality of sets or hands of cards in inclined position, there 120

being an opening formed in each section for holding other cards in inclined position.

4. A counting board comprising a pair of pivotally united hollow sections adapted to receive playing cards, said sections being provided with spaced transversely disposed inclined slats defining slots for the reception of the sets or hands of cards, there being a slot formed in one end of each section and having one wall thereof inclined laterally for holding other cards in inclined position.

5. A counting board comprising a pair of pivotally united sections each provided with spaced transversely disposed inclined slats defining slots adapted to receive a plurality of sets or hands of cards, there being a transverse opening formed in one end of each section for holding other cards in inclined position.

20 6. A counting board comprising pivotally united sections having chambers formed therein and adapted to register with each other for supporting playing cards, said sections being provided with spaced transversely disposed inclined slats defining a

series of slots adapted to receive a plurality of sets or hands of cards, said sections each having one end thereof formed with a slot for supporting other cards in inclined position, and a cover pivotally mounted in each section for closing the last named slot.

7. A counting board comprising a frame the side bars of which are provided with spaced inclined recesses, slats seated in said recesses and extending transversely across the frame and defining slots for the reception of a plurality of sets or hands of cards, there being an opening formed in one end of the frame and having one wall thereof inclined towards the base of the slots for supporting other cards in reverse inclined position.

40 In testimony that I claim the foregoing as my own, I have hereto affixed my signature in the presence of two witnesses.
